GARBAGE CUTTING AND FLUSHING DEVICE

Arvid Bjorklund, Minneapolis, Minn.

Application September 4, 1944, Serial No. 552,706

9 Claims. (Cl. 146—182)

1

My present invention relates to improvements in garbage cutting and flushing devices.

The objects of this invention are: first, to cut kitchen or other garbage into relatively fine particles and thereafter discharge the same into the waste pipe of a sink or other intake leading to a sewer or other place of disposal; second, to provide a water supply and in using part of the water to reduce the garbage, while being cut, to a fluid condition and in using the residue of the water to flush the garbage as the same is emitted from the cutting operation.

Other objects of the invention will be apparent from the following description, reference being had to the drawings.

To the above end, generally stated, the invention consists of the novel devices and combination of devices hereinafter described and defined in the claims.

In the accompanying drawings, which illustrate the invention, like characters indicate like parts throughout the several views.

Referring to the drawings:

Fig. 1 is a view partly in side elevation and partly in longitudinal central vertical section showing one embodiment of the invention;

Fig. 2 is a view partly in elevation and partly in transverse vertical section taken on the irregular line 2—2 of Fig. 1;

Fig. 3 is a fragmentary view of the cutting and conveying rotor removed from the apparatus;

Fig. 4 is a detail view in section taken on the line 4—4 of Fig. 3;

Fig. 5 is an edge elevation of one of the stationary cutting knives removed from the device;

Fig. 6 is a side elevation of the knife shown in Fig. 5;

Fig. 7 is an end elevation of the same;

Fig. 8 is a view partly in side elevation and partly in longitudinal central vertical section showing another embodiment of the invention;

Fig. 9 is a plan view of the invention shown in Fig. 8;

Fig. 10 is a view principally in transverse vertical section taken on the line 10—10 of Fig. 8; and

Fig. 11 is a view partly in end elevation and partly in transverse vertical section taken substantially on the irregular line 11—11 of Fig. 8.

Referring first to the invention shown in Figs. 1 to 7, inclusive, wherein a cutting and conveying rotor is operated by an electric motor:

The numeral 12 indicates a housing having therein a cylindrical compartment 13, for a horizontally disposed cutting and conveying rotor 14,

and a water conduit 15. The compartment 13 is downwardly inclined on its longitudinal axis and the water conduit 15 is directly under said compartment and parallel thereto. On top of the housing 12 is an integral feed hopper 16 arranged to discharge garbage fed thereto directly on top of the rotor 14 at its inner end portion. On the bottom of the housing 12, at the delivery end of the water conduit, is a downturned elbow affording a flushing chamber 17. This elbow is an integral part of the housing 12 and forms a continuation of the water conduit 15.

Access may be had to the interior of the rotor compartment 13 through the open lower end thereof and which end is normally closed by a screw cap 18. An escape opening 19 is formed in the bottom of the rotor compartment 13 through which disintegrated garbage from the rotor 14 is precipitated into the flushing chamber 17. A large communicating passageway 20 between the rotor compartment 13 and the water conduit 15 is formed in the bottom of said compartment.

On the periphery of the rotor 14 is a spiral cutting blade 21 that is ground to a sharp cutting edge and a spiral feed channel formed by said blade. The rotor 14 is carried on a shaft 22 journaled in bearings 23 on the housing 12 and screw cap 18. Said rotor 14 and its shaft 22 are in axial alignment with the rotor compartment 13. A pair of screws 24 having threaded engagement with the bearings 23 hold the rotor shaft 22 against end thrusts. These screws 24 have conical points that extend into correspondingly formed seats in the end of the rotor shaft 22. Co-operating with the spiral cutting blade 21 is a spiral shearing blade or rib 25 integral with the internal wall of the rotor compartment 13.

An electric motor 26 is provided for operating the rotor 14 by means of a worm 27 that meshes with a worm gear 28. The worm 27 is mounted on the armature shaft 29 of the motor 26 and the worm gear 28 is mounted on the rotor shaft 22 at the rear end of the rotor 14. The motor 26 is bolted to a base structure 30 that also affords a support for the housing 12. A guard 31 for the worm 27 extends transversely through the housing 12 in the passageway 20. This guard 31 is in the form of a trough integral with the housing 12 and having in one of its ends a bearing 32 for the armature shaft 29. Formed in the housing 12 at the other end of the guard 31 is an access passageway normally closed by a screw cap 33. The armature shaft 29, at its free end, is supported by a screw 34 having threaded engagement with the cap 33. This screw 35 has a con-

cal point which extends into a correspondingly formed seat in the adjacent end of the shaft 28. In the bottom of the guard 31 is a drain hole 35.

The water conduit 15 leads from a bossed opening 36 in the housing 12 and extends under the guard 31. A water pipe 37, at its delivery end, is screwed into the bossed opening 36 and leads from any suitable source of water supply under pressure, not shown. The bottom of the water conduit 15, under the guard 31, is upwardly inclined to afford a deflecting surface 38 for splashing or spraying water into the rotor compartment 13 through a notch-like opening 39 in the rear end portion of the bottom of said compartment.

A transverse passageway 40, in the form of a notch, is formed in each convolution of the spiral cutting blade 21. As shown, the passageways 40 are in alignment but, if desired, they may be staggered. A waste pipe 41, at its intake end, is screwed into the elbow forming the flushing compartment 17 for conveying flushed garbage from the rotor compartment 13 to a sink or other outlet, to a sewer or other place of disposal. On the outer end of the rotor 14 is an oblique stirring pin 42 that prevents garbage from clogging the space between the respective ends of the rotor 14 and the screw cap 18.

To assist the cutting blade 21 and the shearing blade 25 in disintegrating the garbage, there is provided a plurality of fixed knives 43. These knives 43 are formed on the ends of headed bolts 44 that extend into the housing 12 at the top thereof and have threaded engagement therewith. The knives 43 extend into the spiral groove or channel formed by the cutting blade 21.

Operation

Garbage fed into the rotor compartment 13 through the hopper 16, is deposited directly onto the rotor 14 and then conveyed by its spiral cutting blade 21 with a screw action to the escape opening 19 and precipitated into the flushing chamber 17. During the conveying of garbage by the rotor 14 it is acted upon by the cutting blade 21, the shearing blade 25 and the knives 43, which cuts the same into relatively fine particles. It is important to note that the disintegrated garbage freely passes directly from the rotor 14 into the discharge opening 19.

The major portion of the water discharged into the conduit 15 from the pipe 37 flows to the chamber 17 and flushes the disintegrated garbage precipitated into said chamber from the rotor 14. A relatively small portion of the water discharged from the pipe 37 is sprayed or splashed by the deflecting surface 38 through the passageway 39 and into the rotor compartment 13. This water, upon coming in contact with the garbage in the rotor compartment 13, reduces the garbage as the same is being disintegrated into a fluid condition. The fluid condition of the garbage greatly facilitates its screw-like movement through the rotor compartment 13 by the rotor 14 and its discharge from said rotor. As the disintegrated garbage has a free and unobstructed travel in the rotor compartment 13 and discharge therefrom into the flushing compartment 13, very little power is required to operate the rotor 14.

As the disintegrated garbage is discharged from the rotor compartment 13, the stirring pin 42 prevents packing of the garbage between the respective ends of the housing 12 and the rotor 14 and facilitates its precipitation into the flushing chamber 17.

The passageways 40 in the cutting blade 21 permits the escape of water from one convolution of

the channel formed by the cutting blade 21 to the other in addition to its spiral travel in said channel. This two-course travel of the water greatly facilitates the commingling of the water with the garbage in reducing it to a fluid condition. Furthermore, the sharp shoulders formed on the cutting blade 21 by the passageways 40 assists in breaking up the garbage and commingling the same with the water.

Referring now in detail to the invention shown in Figs. 8 to 11, inclusive, wherein the operation of cutting and reducing the garbage to a fluid condition is the same as that shown and described in Figs. 1 to 7, inclusive, except that the rotor is operated by a water motor and waste water from the motor is used to reduce garbage to a fluid condition and flush the same:

The housing 45, the rotor compartment 46, the water conduit 47, the hopper 48, the elbow 49, the escape passageway 50, the rotor 51, its shaft 52 and spiral cutting blade 53 having transverse notches 54, the spiral shearing rib or thread 55, the knives 56 and the stirring pin 57 are identical or substantially identical with corresponding parts shown in Figs. 1 to 7, inclusive, and perform the same functions.

The open lower end of the rotor compartment 46 is normally closed by a cap 58 attached to the housing 45 by screws 59. Bearings 60 on the housing 45 and the cap 58 are provided for the rotor shaft 52. A screw 61 having threaded engagement with the cap 58 has a conical end, which extends into a correspondingly formed seat in the respective end of the rotor shaft 52 and holds said shaft against downward endwise movement. A waste pipe 62 leading from the elbow 49 is fragmentarily shown by means of broken lines.

Formed in the housing 45 is a water wheel compartment 63 having communication with the rotor compartment 46 and the water conduit 47. Access may be had to the compartment 63 through the open side thereof, which is normally closed by a cover 64 attached to the housing 45 by screws 65. A water wheel 66 is mounted in the compartment 63 and its shaft 67 is journaled in bearings 68 on the housing 45 and the cover 64. The water wheel 66 is provided with circumferentially spaced peripheral pockets 69.

Driving connections from the water wheel 66 to the rotor 51 include a worm 70 on the water wheel shaft 67 that meshes with a worm gear 71 on the rotor shaft 52.

The water wheel 66 is driven by a jet of water discharged from a nozzle 72 into the peripheral pockets 69 as they are successively brought into alignment with said jet. This nozzle 72 is in communication with the delivery end of a water pipe 73 fragmentarily shown by means of broken lines in Fig. 8. Said water pipe 73 leads from any suitable source of water supply under pressure, not shown. The nozzle 72 is screwed into a bossed opening 74 in the housing 45 and the water pipe 73 at its discharge end is screwed into said opening over the nozzle 72. The nozzle 72 is arranged to direct a stream of water into the peripheral pockets 69 substantially tangentially to the water wheel 66. On the back of the housing 45 is a bifurcated lug 75 by means of which said housing may be bolted to a support, not shown. The major portion of the waste water from the water wheel pockets 69 is emptied into the conduit 47 and used for flushing the cut garbage as the same is precipitated from the escape passageway 50. A certain amount of water in the water wheel pockets 69 is carried into the rotor compartment

46 and splashed or thrown on the garbage being cut and reduces the same to a fluid condition.

What I claim is:

1. In a device of the character described, an elongated housing provided interiorly with stationary shearing means, a cylindrical rotor mounted in the housing and provided on its periphery with a continuous spiral cutting blade having a sharp cutting edge cooperating with the shearing means of the housing, a water supply conduit external of the housing, the housing at its ends adjacent the ends of the rotor being provided with passageways communicating with the conduit whereby water admitted into one end of the housing is discharged from the opposite end thereof, a channelway extending through each convolution of the cutting edge of the spiral cutting blade of the rotor, said channelways being cut through the cutting edges of the spiral cutting blade and into the face of the rotor, each of said channelways extending obliquely to the cutting edge through which it passes and being elongated to extend beyond each side of the cutting blade edge, the upper edges of the side walls of said channelways throughout their lengths being sharpened to provide cutting edges, and the cutting edges of the channelways at their points of joinder with the cutting edges of the spiral blade merging into the cutting edges of the rotor blades to form extensions thereof.

2. In a device of the character described, an elongated housing provided interiorly with stationary shearing means, a cylindrical rotor mounted in the housing and provided on its periphery with a continuous spiral cutting blade having a sharp cutting edge cooperating with the shearing means of the housing, a water supply conduit external of the housing, the housing at its ends adjacent the ends of the rotor being provided with passageways communicating with the conduit whereby water admitted into one end of the housing is discharged from the opposite end thereof, a channelway extending through each convolution of the cutting edge of the spiral cutting blade of the rotor, said channelways being cut through the cutting edges of the spiral cutting blade and into the face of the rotor, each of said channelways extending obliquely to the cutting edge through which it passes and being elongated to extend beyond each side of the cutting blade edge, each of the channelways having a concave bottom and divergent side walls, the upper edges of the side walls of said channelways throughout their lengths being sharpened to provide cutting edges, and the cutting edges of the channelways at their points of joinder with the cutting edges of the spiral blade merging into the cutting edges of the rotor blades to form extensions thereof.

3. In a device of the class described, a housing having a horizontally disposed rotor compartment, a water conduit below said compartment and a discharge passageway, said compartment and conduit being in communication with the discharge passageway at their discharge ends, a horizontally disposed rotor mounted in the housing for disintegrating garbage and for conveying and discharging the same into said passageway, and a water motor for operating the rotor, said motor having a wheel constructed and arranged to move upwardly through the inner ends of the conduit and the rotor compartment and empty the major portion of waste water therefrom into the conduit and the residue thereof into the rotor compartment.

4. In a device of the class described, a housing having a rotor compartment, a water conduit directly below the rotor compartment and a flushing chamber with which said compartment and chamber are in direct communication, a stationary spiral shearing blade in the rotor compartment, a horizontally disposed rotor mounted in the rotor compartment and having a peripheral spiral cutting blade cooperating with the shearing blade for disintegrating garbage, said rotor having a spiral channel formed by its cutting blade for conveying garbage and precipitating the same directly into the flushing chamber, and a water motor for operating the rotor, said motor having a wheel constructed and arranged to move directly upwardly through the inner ends of the conduit and the rotor compartment and empty the major portion of the waste water from the motor into the conduit and the residue thereof into the rotor compartment.

5. In a garbage disposal device, a housing having therein a rotor compartment provided with a rotatable rotor for disintegrating garbage and conveying the same longitudinally of the compartment, a water carrying conduit apart from the compartment and having a pair of passageways one of which communicates with the compartment at its forward end and the other with the rear end thereof, a water motor for operating the rotor and embodying a rotatably mounted wheel having thereon water pockets which act as impellers, the pocket impellers of said wheel being movable through the water conduit and the passageway providing communication between said conduit and the forward end of the rotor compartment and through the rotor compartment, and the major portion of the water delivered to said pocket impellers being discharged into the water conduit and the residue of said water being carried into and discharged into the rotor compartment.

6. In a garbage disposal device, a housing having therein a rotor compartment, a water conduit apart from said compartment, a discharge 45 passageway, the discharge ends of the compartment and of the conduit being in communication with said discharge passageway, a rotor in the housing for disintegrating garbage and for conveying the same through the housing and discharging it into the discharge passageway, a water motor for operating the rotor, said motor having a rotatably mounted wheel provided with impellers movable through the water conduit and the inner garbage reception end of the rotor compartment, and of the water operating upon said motor wheel impellers the major portion thereby being discharged into the conduit and the residue of said water being carried by said impellers into the forward end of the rotor compartment and discharged therein.

7. In a garbage disposal device, a housing having therein an elongated substantially tubular rotor compartment, a rotor rotatably mounted in said compartment for disintegrating garbage and conveying the same longitudinally of the compartment, a circular-shaped compartment in said housing beyond the forward end of the tubular rotor compartment and having communication therewith, a water conduit extending across one 70 side of the circular compartment and having an open side in communication with said compartment, said conduit having a discharge end, a passageway providing communication between the discharge end of the conduit and the discharge end 75 of the rotor compartment, a water wheel rotat-

ably mounted in the circular compartment and substantially closing the open side of the water conduit against communication with the circular compartment and the forward end of the rotor compartment, water delivery means to said water conduit, drive connection between said water wheel and said rotor, impellers carried by the water wheel and movable in the open side of the water conduit and through the communicating portions of the circular compartment and rotor compartment, said water supply means directing water against said impellers, said impellers acting to carry a portion of the water delivered to them into the rotor compartment for discharge therein, and the remaining and major portion of the water delivered to said impellers being discharged in the water conduit for discharge from the outlet thereof.

8. A construction as defined in claim 5 wherein, the rotor and the water wheel rotate about axes which are substantially at right angles to one another.

9. In a garbage disposal device, an elongated housing having therein a tubular rotor compartment, a rotor rotatably mounted in said compartment for disintegrating garbage and conveying the same longitudinally of the compartment, said housing beyond the receiving end of the rotor compartment comprising a chamber having therein a gear operatively connected to the rotor, a water conduit at the lower side of the housing and having communication with the housing chamber and the forward receiving end of the rotor compartment, a water discharge, said water conduit being connected to said discharge and a passageway connecting the discharge and the discharge end of the rotor compartment, a second gear having driving connection with the first gear, power means for driving said second gear, said second gear being located beneath the first gear,

10
